SCREW AND NUT MECHANISM

Charles L. Shull, Horseheads, N. Y.

Application February 19, 1949, Serial No. 77,380

3 Claims. (Cl. 74—424.8)

1

The present invention relates to a variable electrical capacitance, and more particularly to a trimmer condenser for use in connection with tuned radio-frequency electrical circuits.

Variable condensers of this general type are commonly formed of telescoping cylindrical members separated by an air space or by other suitable dielectric material such as a vitreous, ceramic or plastic tube. In order to vary the capacity of the condenser, the inner electrode is adjusted longitudinally with respect to the outer electrode so as to increase or decrease the amount of overlap between them, this being usually accomplished by some form of threaded connection to facilitate fine adjustment.

In devices of this type as heretofore constructed however, it has been difficult to secure smooth adjustment, free from fluctuation and/or microphonic noises due to wobbling or irregular movements of the movable electrode, particularly when the threaded adjusting means therefor requires that the electrode be rotated in order to vary the capacity of the condenser.

It is an object of the present invention to provide a novel variable condenser of the tubular type which is simple in construction, efficient in operation and economical to manufacture.

It is another object to provide a device in which the variations of capacity take place smoothly and without fluctuations or microphonic disturbances.

It is another object to provide such a device in which the movable electrode is arranged to slide into and out of the outer electrode without relative rotation or wobbling.

Further objects and advantages will be apparent from the following description taken in connection with the accompanying drawing in which:

Fig. 1 is a side elevation, partly broken away and in section, of a preferred embodiment of the invention;

Fig. 2 is an end view thereof;

Fig. 3 is a section taken substantially on the line 3—3 of Fig. 1;

Fig. 4 is a detail in perspective of the mounting bushing for the condenser prior to the insertion of the control nut therein, together with the anchorage means for the bushing shown separate therefrom; and

Fig. 5 is a detail in perspective of the square threaded adjusting bar.

In Fig. 1 of the drawing there is illustrated a tube 1 of suitable dielectric material such as glass, having an outer electrode 2 mounted there-

on and extending from one end thereof substantially to the middle of the tube. The electrode 2 may be a metallic cylinder, or a metallized coating of the glass, and is preferably provided with a connector 3 which may be soldered or otherwise suitably anchored and fixed to the end of the tube and the electrode.

An inner electrode 4 of suitable material such as Invar is slidably mounted within the tube 1, and means are provided for moving this inner electrode longitudinally to adjust its telescopic relation with the outer electrode 2 in order to vary the capacity of the condenser. As here shown, this means comprises a shaft or bar 5 of uniform non-circular cross section, a square cross section as illustrated being preferred. Electrode 4 is rigidly mounted on one end of the bar 5 in any suitable manner as by crimping the bar in a counter-bore thereof as indicated at 6.

20 The bar 5 extends outside of the tube 1, and a bearing bushing 7 therefor is suitably fixed to the end of said tube as by soldering to a metallized coating thereon as shown at 8. The bushing 7 has a non-circular central bore 9 con-

forming closely to the bar 5 and slidably receiving said bar while preventing relative rotation. The angular edges of the bar 5 are threaded as shown at 11, and a nut 12 is threaded on said bar and has an enlarged portion 13 seated in a counterbore 14 in the outer end of the bushing 7 and retained therein by lips or flange members 15 (Fig. 4) which are bent down over the end of the enlarged section 13 after the same has been inserted in the counter-bore of the bushing. A flexible washer 16 is preferably interposed between the inner end of the nut 12 and the bottom of the counter-bore 14 in order to prevent lost motion of the nut with respect to the bushing 7 and also to frictionally resist rotation of the nut so as to maintain the adjustment of the condenser. The portion of the nut which extends outside the bushing is preferably formed with flats or slots 20 to receive a spanner or wrench to facilitate adjustment.

35 40 45 The bushing 7 is arranged to be rigidly mounted in a panel or chassis member such as indicated at 17. For this purpose, the bushing is provided with a portion 18 having a non-circular external conformation which may comprise one or more flats 19, adapted to be received in an opening 21 in the panel 17 having a similar conformation. A shoulder 22 is arranged to engage one side of the panel 17, and an elastic U-shaped retaining member 23 is adapted to be slidably received in a groove 24 in the bushing and bear against the opposite side of

50 55

the panel to thereby hold the bushing rigidly assembled in the panel.

It will be readily appreciated that the smooth flat surfaces of the square bar 5 form an excellent bearing in the square bore of the bushing 7, while the spring-loaded nut 12 assists in maintaining the alignment of the bar in the bushing while cooperating with the threaded corners of the bar to provide a convenient and accurate means for adjusting the bar 5 and electrode 4 longitudinally. 10

Although but one form of the invention has been shown and described in detail, it will be understood that other embodiments are possible, and changes may be made in the precise form and arrangement of the parts without departing from 15 the spirit of the invention.

What is claimed is:

1. In a variable electrical condenser or the like, mounting and adjusting means for the condenser comprising a bearing bushing having an opening therethrough of polygonal cross-section, a bar of similar cross-section slidably mounted therein, the angular edges of the bar being screw-threaded, said bushing having an enlarged cylindrical counterbore in one end; a nut threaded on the bar having an enlarged portion seated in the counterbore of the bushing, said bushing having a terminal flange embracing the end of the enlarged portion of the nut to retain it in the counterbore while permitting rotation thereof to traverse the 30 threaded bar, the exterior of the bushing having a cylindrical surface provided with a flattened portion and a radial flange adjacent thereto, a fixed panel having an opening conforming to the flat-

tened cylindrical surface, and detachable elastic means for clamping the bushing in said opening with the flange bearing on the panel.

2. Mounting and adjusting means as set forth in claim 1, including further an elastic compression member seated in the bottom of the counterbore in the bushing and bearing against the end of the nut to remove backlash between the nut and bushing, and to frictionally maintain the adjustment of the nut and bar.

3. Mounting and adjusting means as set forth in claim 2 in which the projecting portion of the nut is formed to receive a rotary adjusting tool, and including further means for non-rotatably mounting the bushing in a fixed support.

CHARLES L. SHULL.
